UNITED STATES PATENT OFFICE.

DAVID E. CONRAD, OF ELDON, IOWA, ASSIGNOR OF ONE-HALF TO VAN V. BALDWIN,
OF ELDON, IOWA.

CAR DOOR.

Application filed June 11, 1925. Serial No. 36,469.

To all whom it may concern:

Be it known that I, DAVID E. CONRAD, a citizen of the United States, residing at Eldon, in the county of Wapello and State of Iowa, have invented certain new and useful Improvements in Car Doors, of which the following is a specification, reference being had to the accompanying drawings.

This invention relates to doors such as are used on railroad cars, and particularly to those doors which are supported upon rollers.

In stock cars, grain cars and cars for carrying freight, the doors ordinarily hang on rollers and are held closed by hasps. These hasps are easily broken by sudden starts and stops of the train and the rollers very liable to wear out and then the door cannot be moved without using a pry for shifting the door. This damages the side of the car and the door casings. If a very heavy hasp is used, the piece to which the hasp is attached is often broken out of the door. In many cases where perishable freight is being shipped, the car doors must be cleated open. No cleat in this position will stand the movement of heavy trains, the backing and sudden stopping, and there is no way to seal the car and under these circumstances there is considerable loss in the contents of the cars. In many cars the doors are left entirely open and the doors are then liable to run backward and forward and not only the doors are damaged but accidents often happen from the rolling car door.

The general object of this invention is to overcome this difficulty and provide a car door which is mounted upon rollers but which under normal circumstances and when the car is traveling is supported out of engagement with the rollers and is held from any movement longitudinally of the car.

A further object is to provide a car door construction which obviates the necessity of using hasps or other locking devices of like character.

A still further object is to provide a construction of this character wherein the door is locked both at top and bottom and in which the door may be locked either fully closed or partially closed to any extent required.

Another object is to provide a car with means whereby when the door is closed the door shall be forced toward the door frame,

thus holding the door closed tightly and preventing rain, snow or dust from entering the car but in which, when the door is raised and moves by means of its rollers upon the track, the upper portion of the door will be automatically forced away from the door frame, thus permitting the ready shifting of the door on its track to open or close the door.

Still another object is to provide a construction of this character in which the door carries the rollers and a track is provided which is movable vertically to engage the rollers and support the door on the rollers whereby the door may be shifted longitudinally of the car, and in which the track is manually lowerable to remove the track from its engagement with the rollers and thus take the weight off the rollers and permit the door to be locked.

Other objects will appear in the course of the following description.

My invention is illustrated in the accompanying drawings, wherein:

Figure 1 is a side elevation of a car constructed in accordance with my invention showing my improved doors applied thereto;

Figure 2 is a section on the line 2—2 of Figure 3 showing the door closed;

Figure 3 is a like view to Figure 2 but showing the door after the rail has been raised;

Figure 4 is a front elevation of a portion of the door and its frame showing the means for raising the rail;

Figure 5 is a perspective view of the bracket and the lower rack;

Figure 6 is a fragmentary perspective view of the rail at one end thereof;

Figure 7 is a section on the line 7—7 of Figure 1.

Referring to the drawings, A designates the side of a railroad car having the door opening B. Adapted to be shifted over this door opening are the double doors 10, it being understood that while I have illustrated double doors that a single door might be used in place of the double doors. Each of these doors 10 is formed on its upper margin and upon its outside face with an outwardly projecting flange 11 which may be made of metal or any other suitable material and which is formed with an outwardly and upwardly inclined toothed face 12. This flange may be, as before remarked,

preferably of metal and may be attached to the door in any suitable manner.

Disposed over the top of the door is the hood 13 which extends longitudinally of the car above the opening B and has a length equal to the full movement of the two doors 10. This hood 13 extends downward in front of the flange 11 and at its lower end is formed with the flange 14 triangular in cross section like the flange 11, this flange 14 being formed with upwardly facing, downwardly inclined teeth 15. These teeth 15 and the teeth 12 are adapted to mesh with each other, and preferably the teeth 15 extend along the whole face of the flange 14 and preferably the teeth 12 may extend along the entire face of the flange 11, it being understood, however, that while it is preferable to have these interengaging teeth, yet I do not wish to be limited to this for reasons which will hereafter appear.

The lower margin of each door 10 is provided with a plurality of rollers 16, two being shown for each door 10, each roller being held in place by a suitable bearing stud 17 and by a bracket 18 held in place by a bolt 19 or equivalent mechanism. The lower margin of each door carries the longitudinally extending strip 20 which extends out beyond the face of the door in spaced relation to the roller 16, and just below this strip there is disposed the downwardly extending flange 21 which is triangular in cross section and is formed on its under face with the downwardly and inwardly extending gear teeth 22.

Mounted below the door opening B are a plurality of brackets 23, which brackets are recessed on their inner faces, as at 24, and support in this recessed portion the rack 25 which is triangular in cross section and has the downwardly and inwardly extending teeth 26 with which the teeth 22 are adapted to mesh when the door is lowered. Extending downward from each bracket are the two screws, stud bolts or like members 27 and 27^a, and mounted upon these stud bolts is the rail 28, the upper margin of which is inwardly turned, as at 29, and disposed between the outwardly projecting portion of the strip 20 and the rollers 16. The rail 28 is formed with longitudinal, relatively wide slots 30 through which the lower stud bolts 27^a extend, these stud bolts being less in diameter than the width of the slot 30. Above the slot 30 the rail is formed with a plurality of cam-shaped slots 31, these slots extending longitudinally, then upward and longitudinally, and then longitudinally parallel to the top of the rail, and through these slots the stud bolts 27 extend. Preferably the stud bolts 27 and 27^a carry the bushings 32 upon which the walls of the slots operate constituting rollers. The rail is held in place by an outer, longi-

tudinally extending plate 33, this plate being carried by the stud bolts 27 and 27^a and extending the entire length of the rail 28 and holding this roller in place from any lateral movement. The rail 28 is provided at one end with a lug 34 and a lever 35 is pivoted upon the side of the car and is pivotally connected to this lug by means of the link 36. The lever is designed to be locked in any desired position.

With this construction it is obvious that when the rail 28 is lowered, the door will move downward until the toothed faces 22 and 26 of the members 21 and 25 respectively will engage. Then the door will be locked from longitudinal movement. The same thing will be true with regard to the toothed faces 12 and 15 of the flanges 11 and 14 so that when the door is lowered the upper margin of the door and the lower margin of the door will both be lockingly engaged with the housing 13 at the top and with the brackets 23 by means of the rack 25 at the bottom. While I preferably have these members 11, 14, 21 and 25 formed with toothed faces like gear teeth, I do not wish to be limited to this as these faces might simply be roughened and even if the faces are entirely smooth there will be considerable friction that will tend to prevent any easy opening movement of the door.

It will be obvious that when the door is lowered by the downward movement of the track 28, the inclined faces of the members 11 and 21 will tend to move downward on the inclined faces of the members 14 and 23. Thus the door through its weight will be forced tightly against the face of the door frame. It is desirable that when the door is lifted and is in position to operate upon the track 28 that the door should be free from engagement with the face of the door frame. To this end I mount upon the upper margin of the door frame just beneath the housing 23 the longitudinally extending member 37, and when the door is raised the upper margin of this door will engage against the face of this member 37 and the upper margin will be thrown outward, as illustrated in Figure 3, the lower portion of the door rocking upon the pivot formed by the rollers 16 engaging with the flange 29 of the roller 28. Thus the greater portion of the door will be lifted entirely away from and free from contact with the face of the door and the door will be free to be lifted longitudinally.

It will be seen that with this construction the rollers are always in good condition inasmuch as there is but very little wear upon them and they do not support the door at all times and under traveling conditions and carry the door only when the door is in position to be moved. Furthermore the door, when the track is lowered by

its own weight, is forced inward against the face of the car or door frame and then the door is held tightly closed. At the same time the door cannot be shifted longitudinally because of its locking engagement at its top and bottom with the toothed members 14 and 25. There is no necessity of locking the door except in so far as locking the handle is concerned, and it is obvious that the door may be held either fully closed, partially open or fully open just as desired, and that furthermore the door will be held not merely at one or two points but along its whole upper and lower edges against longitudinal movement due to shocks and jars incident to travel. It will be seen that there is no wear either on the rail or on the rollers so that when the rail is lifted and the rollers engaged therewith, the rails will have a perfectly smooth track to travel on and as a consequence the doors may be readily opened.

The inside of the door may be also formed at its opposite ends with a relatively shallow, inwardly projecting flange or rib 38 and the face of the door frame may be formed with a corresponding groove 39, and thus when the door is forced inward or into the position shown in Figure 2, this rib 38 will fit within the groove 39, making a water-tight joint between the inner face of the door and the door frame. Of course, this will only be effective when the door is fully closed and in a certain definite position. The housing 13 covers the door and shelters the top of the door and prevents the entrance of water, snow or the accumulation of ice between the upper margin of the door and the door casing and this housing will give or yield so as to compensate for slight differences in the height of doors. If desired, the members 11, 14, 21 and 25 can have smooth surfaces instead of teeth and still be effective, as in this case the weight of the door will create so much friction between these faces of the two members 21 and 25 or 11 and 14 that it will be practically impossible to shift the door without the exercise of very great pressure without the door being raised up.

It is to be also noted that each roller 16 is formed with a flange 16^a and that the junction of the flange 29 with the track 28 is rounded or beveled and it will thus be seen that when the track is raised the beveled corner of the track will ride upon the beveled edge of the flange 16^a and this will tend to draw the lower portion of the door away from actual contact with the side of the car and allow the door to move with ease.

The front plate and the rail, it will be seen, are both provided with openings which are adapted to register with each other when the rail has been shifted to allow the door

to fall and when these openings are in register with each other and the door, therefore, held from any longitudinal movement, the rail may be locked from longitudinal movement or a sealing device placed through these coincident openings 40 and 41.

While I have illustrated certain details of construction and arrangement of parts which I believe to be particularly effective for the purpose intended, I do not wish to be limited to these details nor to the exact arrangement as it is obvious that these may be changed in many ways without departing from the spirit of the invention as defined in the appended claims. It is obvious that this principle of supporting the doors and locking the doors in their closed or partially closed position may be used on freight cars, automobile cars, grain cars, and in many other situations where it is desirable to provide a sliding door and provide simple means whereby the door may be locked. Thus, for instance, in barns where the door opening is closed by sliding doors running upon rollers it is often the case that the weight of the door causes the track and the hangers to be deformed and this causes the door to run badly and with difficulty. Under these circumstances an attempt to open or close the door very often shoves the rollers off the track entirely. This cannot occur with my door inasmuch as the lower edge of the door is always held from any too great outward movement by the member 25 and the upper margin of the door is held from too great outward movement by the overhang of the housing and of the toothed member 14. At the same time by removing the housing 13, the door may be readily withdrawn from its engagement with the structure having the door opening.

It will be seen from Figure 2 that when the rail 28 is lowered it will extend over the flange 20 and closely adjacent thereto so that the door cannot be lifted up by any other means and can only be raised to the position shown in Figure 3 by unlocking the rail 28 and shifting the rail longitudinally.

The device is simple to install, is composed of relatively few parts and these of such character that they may be cheaply made.

I claim:—

1. In a door structure, a wall having an opening, a door therefor, rollers on the door, a track extending parallel thereto and mounted thereon for vertical movement into or out of engagement with the rollers, manually operable means for shifting said track, and a supporting member disposed directly below the lower edge of the door and on which the door rests and is supported when the track is lowered.

2. In a door structure, a wall having an

opening, a door therefor, rollers on the door, a track extending parallel to the wall and mounted thereon for vertical movement into or out of engagement with the rollers, 5 manually operable means for shifting said track, a door support disposed directly below the lower edge of the door and on which the door rests and is supported when the track is lowered, and means carried upon 10 the wall above said opening operatively engaging the door when the door is lowered and thus limiting the outward movement of the upper margin of the door.

3. In a door structure, a wall having an 15 opening, a door therefor, rollers on the door, a track extending parallel to the wall and mounted upon the wall for vertical movement into or out of engagement with the rollers, manually operable means for shifting 20 the track, a door support disposed directly below the lower edge of the door and upon which the door rests when the track is lowered, said door support being beveled downward and inward to thereby 25 cause the door to shift through gravity toward the wall.

4. In a door structure, a wall having an 30 opening, a door therefor mounted upon the opening for vertical movement, rollers on the door, a track mounted upon the wall for vertical movement into or out of engagement with the rollers and adapted, when raised, to engage said rollers and lift the door and, when lowered, to lower the door 35 and then disengage from said rollers, manually operable means for shifting said track, and means having a length substantially equal to the length of movement of the door for supporting the door when the track 40 is lowered, said supporting means when the door is lowered acting to lock the door from longitudinal movement in any position of the door.

5. In a door structure, a wall having an 45 opening, a door therefor, rollers on the door, a track mounted upon the wall for vertical movement into or out of engagement with the roller, means permitting limited outward movement of the upper 50 margin of the door but limiting the downward movement of the door, means supporting the door when it is lowered, manually operable means for shifting the track, and means causing the outward movement 55 of the top of the door when the door is raised.

6. In a door structure, a wall having an 60 opening, a door therefor, rollers carried by the door, a track operatively supported upon the wall below said rollers for vertical movement into or out of engagement with the rollers, manually operable means for shifting said track, a supporting member disposed below and exteriorly to the 65 upper margin of the door, a supporting

member disposed below the lower edge of the door, the door having vertical movement as the track is lowered or raised into or out of engagement with said supporting members, said supporting members being 70 so constructed as to cause the door to move inward when the door is lowered onto the supporting members.

7. In a door structure, a wall having an 75 opening, a door therefor, rollers carried by the door, a track operatively supported upon the wall below said rollers for vertical movement into or out of engagement with the rollers, manually operable means for shifting said track, a supporting member 80 disposed below and exteriorly to the upper margin of the door, a supporting member disposed below the lower edge of the door, the door having vertical movement as the track is lowered or raised into or out of 85 engagement with said supporting members, said supporting members being so constructed as to cause the door to move inward when the door is lowered onto the supporting members, and means causing the outward movement of the top of the door 90 as the door is lifted by the track from said supporting members.

8. In a door structure, a wall having an 95 opening, a sliding door therefor, means supporting the door for sliding movement longitudinally of the wall, said means permitting the door to move vertically, the upper margin of the door being formed 100 with a longitudinally extending outwardly projecting member having an inwardly and downwardly inclined surface, the lower edge of the door being formed with a longitudinally extending member having a 105 downwardly and inwardly inclined surface, and upper and lower longitudinally extending members carried by the wall, said members each having downwardly and inwardly inclined surfaces with which the 110 surfaces of said first named members on the door are adapted to engage when the door is lowered.

9. In a door structure, a wall having an 115 opening, a door therefor mounted upon the wall for longitudinal movement and limited vertical movement, manually operable means for raising or lowering the door, and means locking the door from longitudinal movement when the door is lowered, said 120 means including longitudinally extending members carried on the door, and confronting longitudinally extending members supported upon the wall, the confronting faces of said wall and door members being downwardly and inwardly inclined.

10. In a door structure, a wall having an 125 opening, a door therefor mounted upon the wall for longitudinal movement and limited vertical movement, manually operable 130 means for raising or lowering the door,

- means locking the door from longitudinal movement when the door is lowered, said means including members carried on the door, and confronting members supported upon the wall, said confronting faces of the door and wall members having interengaging corrugations.
11. In a door structure, a wall having an opening, a door therefor mounted upon the wall for longitudinal movement and limited vertical movement, manually operable means for raising or lowering the door, means locking the door from longitudinal movement when the door is lowered, said means including members carried on the door, and confronting members supported upon the wall, said confronting faces of the door and wall members being formed with downwardly and inwardly inclined toothed faces.
12. In a door structure, a wall having an opening, a door therefor, means supporting the door upon the wall for longitudinal movement and for limited vertical movement, rollers carried by the door and a longitudinally movable track mounted upon the wall, manually operable means for shifting the track longitudinally, a longitudinally extending member mounted upon the upper margin of the door and having a downwardly and inwardly extending toothed face, a housing mounted upon the wall above the door opening and extending outward beyond said member and at its lower end carrying a longitudinally extending member having a downwardly and inwardly beveled face which the first named member confronts, a member carried upon the lower edge of the door and having a downwardly and inwardly inclined face, a longitudinally extending member operatively supported upon the wall below the door opening and having a downwardly and inwardly inclined face confronting the face of the last named member, and means causing the upward movement of the track into contact with the rollers upon the longitudinal movement of the track in one direction and the lowering of the track out of contact with the rollers upon a movement of the track in the other direction.
13. In a door structure, a wall having an opening, a door therefor mounted upon the wall for longitudinal movement and limited vertical movement, manually operable means for raising or lowering the door, means locking the door from longitudinal movement when the door is lowered, said means including members carried on the door, and confronting members supported upon the wall, said confronting faces of the door and wall members being formed with downwardly and inwardly inclined toothed faces.
14. In a door structure, a wall having an opening, a door therefor, rollers mounted upon the lower margin of the door, brackets mounted below the door opening, means carried by the brackets and mounted directly below the door for supporting said door when the door is lowered, a track mounted upon the brackets and beneath the rollers, and manually operable means for causing the lifting of the track into engagement with the rollers and the successive lifting of the door from its support or causing the descent of the track and the lowering of the door onto said support.
15. In a door structure, a wall having an opening, a door therefor, rollers mounted upon the lower margin of the door, brackets mounted below the door opening, means for supporting said door when the door is lowered, a track mounted upon the brackets and beneath the rollers, the track being mounted for longitudinal movement and having cam slots and the brackets being provided with pins engaging said cam slots and whereby, as the track is moved longitudinally in one direction, the track will rise into engagement with the rollers and lift the door from its support and in the other direction the track will be lowered and permit the lowering of the door onto said support.
16. In a door structure, a wall having an opening, a door therefor, rollers on the lower margin of the door, brackets disposed below the lower margin of the door, said brackets supporting a longitudinally extending member having a downwardly and inwardly inclined face and the lower margin of the door being formed with a lower downwardly and inwardly inclined face confronting the face of said member, means operatively engaging the upper margin of the door and preventing outward movement of the upper margin of the door, a track disposed against said brackets and having longitudinally extending slots, pins passing through the slots into the brackets, certain of the slots having inclined portions, manu-

- ally operable means for shifting the track longitudinally to thereby cause the inclined portions of the slots to ride upon said pins and cause the lifting of the track into engagement with the rollers and the successive lifting of the door from said support or the lowering of the door onto said support and the disengagement of the track from the rollers.
- 10 17. In a door structure, a wall having an opening, a door therefor, rollers on the lower margin of the door, brackets disposed below the door opening and having outwardly projecting pins, a track having longitudinally extending slots through which said pins pass, certain of the slots having upwardly inclined cam portions, manually operable means for shifting said track longitudinally, the upper margin of the track being inwardly bent and being disposed beneath the rollers on the door, and means preventing the outward movement of the door at its upper margin but permitting the vertical movement of the door.
- 15 18. In a door structure, a wall having an opening, a door therefor, rollers on the lower margin of the door, brackets disposed below the door opening and having outwardly projecting pins, a track having longitudinally extending slots through which said pins pass, certain of the slots having upwardly inclined cam portions, manually operable means for shifting said track longitudinally, the upper margin of the track being inwardly bent and being disposed beneath the rollers on the door, a door-supported member carried upon said tracks, means preventing the outward movement of the door at its upper margin but permitting the vertical movement of the door including a housing extending from the wall over the upper margin of the door and having a longitudinally extending member, and a longitudinally extending member mounted upon the upper margin of the door and confronting the first named member.
- 20 19. A door structure, a wall having a door opening, certain margins of the wall being formed with grooves, a door slidingly supported upon the wall, certain margins of the door being provided with outwardly extending ribs, a vertically movable track mounted upon the wall, rollers carried by the door, the track being engageable with the rollers when the door is lifted, and means supporting the door when the track is lowered, said means causing the door to move inward and bring the ribs of the door into engagement with the grooves in the wall.
- 25 20. In testimony whereof I hereunto affix my signature.

DAVID E. CONRAD.
